United States Patent Office

Des. 225,577
Patented Dec. 19, 1972

225,577

TAPE APPLICATOR

Elvin L. Boyce, Salt Lake City, Utah, assignor to Tape-
Licator, Inc., Salt Lake City, Utah

Filed June 17, 1971, Ser. No. 154,252

Term of patent 14 years

Int. Cl. D19—02

U.S. Cl. D74—1

FIG. 1

FIG. 2

FIG. 3

FIG. 6

FIG. 4

FIG. 5

FIG. 1 is a perspective view of a tape applicator showing my new design;

FIG. 2 is a side view thereof, the opposite side is substantially the same in appearance as the side shown;

FIG. 3 is a top view thereof;

FIG. 4 is a front view thereof;

FIG. 5 is back view thereof; and

FIG. 6 is a bottom view of the tape applicator.

I claim:

The ornamental design for a tape applicator, as shown and described.
